UNITED STATES PATENT OFFICE.

HARVEY HUESTIS, OF PROVIDENCE, RHODE ISLAND.

DESIGN FOR A SETTING FOR JEWELRY.

SPECIFICATION forming part of Design No. 18,633, dated September 25, 1888.

Application filed April 12, 1888. Serial No. 270,487. Term of patent 7 years.

To all whom it may concern:

Be it known that I, HARVEY HUESTIS, residing at Providence, in the county of Providence and State of Rhode Island, have invented 5 and produced a new and original Design for Settings for Jewelry, of which the following is a full, clear, and exact description, reference being had to the accompanying drawings, forming part of this specification.

- 10 Figure 1 is a perspective view of a ring provided with my new setting for jewelry. Fig. 2 is a side view of my newly-designed setting. Fig. 3 is a plan view of my newly-designed setting.
- 15 The leading feature of my design consists in a number of groups of raised points or projections having flat tops and surrounding the jewel, said groups being divided from each other by a space.
- 20 In the drawings, 4 is the jewel; 5 5, the raised points, of square or oblong section, having the flat tops 6, and divided from each other by the space 7, having the semicircular bottom 8.
- 25 In the setting shown in the drawings the

points are in groups, there being four points on each side and three at each end, the side group being separated from the end group by the rounded beveled corner 9. As the beveled corners clearly define and separate one 30 group from the other, the points appear to the eye clear and distinct, presenting an agreeable appearance and enhancing the beauty and outline of the stone or jewel.

Having thus described my new and original 35 design, I claim as new and desire to secure by Letters Patent—

The design for jewelry-settings herein shown and described, the same consisting in a number of raised flat-topped points, 5, which are 40 separated from each other by semicircular spaces 8 and arranged in groups, the groups of points being separated by beveled corner spaces, substantially as shown and described.

In witness whereof I have hereunto set my 45 hand.

HARVEY HUESTIS.
